CONVERTIBLE LADDER

Herbert L. Garner, Sheridan, Ark.

Application November 8, 1949, Serial No. 126,158

1 Claim. (Cl. 228—23)

1

This invention relates to ladders, and more particularly to a ladder which can be arranged as a stepladder in either an open or a folded condition and converted into a straight ladder materially longer than the stepladder, when desired.

It is among the objects of the invention to provide an improved ladder of highly simplified construction which can be used as a stepladder, can be extended from such stepladder arrangement into a straight ladder and securely locked in such straight condition, and can be folded to a compact form for transportation or storage, and which is strong and durable in construction, economical to manufacture, of readily available material, of light weight, and fully effective to serve the purposes of two different types of ladders when used in such operations as house painting and cleaning.

Other objects and advantages will become apparent from a consideration of the following description and the appended claim in conjunction with the accompanying drawing, wherein:

Figure 1 is a side elevation of a convertible ladder illustrative of the invention showing the ladder in full lines as a stepladder in open condition, and in broken lines as a straight ladder in extended condition;

Figure 2 is a longitudinal, medial cross-section of the ladder in folded condition; and

Figure 3 is a rear elevation of a fragmentary upper portion of the ladder in folded condition, as illustrated in Figure 2, with portions broken away and shown in cross-section to better illustrate the construction thereof.

With continued reference to the drawing, the ladder comprises, in general, two sections 10 and 11 with the section 11 pivotally connected at one end to the section 10 at a location spaced from one end of the latter section, a platform 12 pivotally connected to one section at a location spaced from the pivotal connection between the two sections and engageable with the other section to hold the two sections in the relative position illustrated in full lines in Figure 1 in which they diverge from their pivotal connection and constitute a stepladder in open condition, and means 13 carried by the section 10 and engageable with the section 11 to releasably secure the section 11 in longitudinal alignment with the section 10, as illustrated in broken lines in Figure 1, to constitute a straight ladder longer than the stepladder shown in full lines.

The ladder section 10 comprises two elongated, flat rails 14 and 15, each having substantially parallel longitudinal edges and both being se-

2

cured together in spaced-apart, substantially parallel relationship by the ladder steps.

The bottom ends of the two sections 10 and 11 are inclined, as indicated at 16 and 17 in Figures 1 and 2, at an angle complementary to the angle between the two sections when held in the position illustrated in full lines in Figure 1 by the platform 12, so that when the ladder is supported in upright position as an open stepladder, the bottom ends of the rails of the two sections will engage a horizontal surface substantially throughout the width of such bottom ends of the rails.

The lower steps, as indicated at 18, 19, 20, 21 and 22, of the section 10, extend inwardly from the outer longitudinal edges of the rails 14 and 15 and are set at an angle to the outer longitudinal edges of the rails substantially the same as the angle between such outer longitudinal edges and the bottom ends of these rails, so that these lower steps will be substantially horizontal both longitudinally and transversely when the ladder is in the condition and position illustrated in full lines in Figure 1.

23 The upper rungs of the section 10, as indicated at 23 and 24, are secured at their respectively-opposite ends to the rails 14 and 15 on the outer longitudinal edges of these rails, and have their faces substantially parallel to the outer longitudinal edges of the rails. Bolts 25 and 26 extend through the respectively-opposite ends of the top step or rung 24 and through the rails 14 and 15, respectively, at the upper ends of these rails to firmly secure the top rung 24 to the rails and at the same time, reinforce the rails against splitting or cracking when subjected to load with the ladder in extended or straight condition.

27 The ladder section 11 comprises two flat rails 27 and 28 having substantially parallel longitudinal edges and a width substantially equal to the width of the rails 14 and 15 of the section 10. These rails 27 and 28 of the section 11 are secured together in spaced-apart, substantially parallel relationship by a plurality of uniformly spaced-apart steps or rungs, as indicated from 29 to 33, secured at their respectively-opposite ends to the rails 27 and 28 on the longitudinal edges of the rails 27 and 28 opposite the edges of the rails 14 and 15 to which the rungs 23 and 24 are secured, when the section 11 overlaps the section 10 in the folded condition of the ladder, as illustrated in Figure 2.

55 The platform 12, for holding the two ladder sections in operative position to constitute a stepladder, comprises two spaced-apart, substantially

parallel battens 34 and 35, with the batten 34 pivotally connected at one end to the side rail 21 of the ladder section 11, and the batten 35 pivotally connected at one end to the side rail 28 of the ladder section 11 at locations spaced substantially the same distance from the upper ends of the rails 27 and 28, and a plurality of strips 36 secured at their respectively-opposite ends to the battens 34 and 35 at the upper edges of these battens and extending substantially at right angles to the to the battens and from one end thereof to the other. Adjacent its free end, each batten is provided with a suitable formation, illustrated as two downwardly-extending pins 37 spaced apart to receive the top horizontal step 22 of the ladder section 10 therebetween, so that, when the ladder is in the position illustrated in full lines in Figure 1 for use as a stepladder, these pins may engage the top horizontal step 22 of the section 10 and securely hold the sections 10 and 11 at the proper angle relative to each other for use as a stepladder.

Each of the rails 27 and 28 of the ladder section 11 is provided, near its end pivotally connected to the corresponding rails of the section 10, with a transversely-elongated slot, as indicated at 38 and 39 in Figures 1 and 2, and the side rails 14 and 15 of the section 10 are provided at locations spaced from their upper ends with apertures 40 and 41 registerable respectively with the slots 38 and 39. Bolts 40 and 41 extend through the apertures in the side rails 14 and 15, respectively, and through the slots in the side rails 27 and 28, respectively, to pivotally connect the ladder section 11 at its upper end to the ladder section 10 near the upper end of the latter.

It will be noted that the slots 38 and 39 provide a construction wherein the bolts 40 and 41 are substantially at the mid-width location of the ladder rails 27 and 28 when the ladder is in operative condition either as a stepladder or a straight ladder, as illustrated in full and broken lines in Figure 1, but are located adjacent the inner longitudinal edges of these side rails when the ladder is in folded condition, as illustrated in Figure 2, so that the side rails of the ladder section 11 can contact the inner or rearward edges of the steps or rungs 13 to 22 inclusive, of the section 10 with the rails of the section 11 overlapping and substantially parallel to the rails of the section 10 to thereby reduce the ladder to its most compact form for transportation and storage.

In order to convert the ladder from either its completely folded or partly folded condition to its straight condition, the section 11 is pivoted about the bolts 40 and 41 until the edges of its rails 27 and 28, to which the rungs 29 to 33 inclusive, are attached, contact the under or rearward side of the top rung 24 of the section 10, whereupon the section 11 will extend outwardly from the section 10 substantially in longitudinal alignment therewith, as illustrated in broken lines in Figure 1. The means 13 for releasably securing the ladder sections in this relative position comprises two buttons pivotally secured respectively to the side rails 14 and 15 of the section 10 adjacent the top rung 24, but at the opposite edges of the side rails from this rung. The ladder thus has two operative positions, in one of which it constitutes a stepladder, and in the other of which it constitutes a straight ladder, and has in addition, a compact folded condition in which it occupies a minimum amount of space and is easy to carry or store.

It will be noted that the side rails 14 and 15 of the section 10 are spaced apart sufficiently to receive the section 11 therebetween.

The invention may be embodied in other specific forms without departing from the spirit or essential characteristics thereof. The present embodiment is, therefore, to be considered in all respects as illustrative and not restrictive, the scope of the invention being indicated by the appended claim rather than by the foregoing description, and all changes which come within the meaning and range of equivalency of the claim is, therefore, intended to be embraced therein.

What is claimed is:

A convertible ladder comprising a first section including a pair of spaced apart and substantially parallel side rails, steps disposed between said side rails at equally spaced intervals along the latter and secured at their respectively opposite ends to the side rails, said steps being substantially parallel to each other and extending transversely of said side rails from corresponding edges thereof a distance intermediate the width of the side rails, and at least one ladder rung extending between said side rails near one end of said first section and disposed on the edges of said side rails from which said steps extend, a second section receivable between the side rails of said first section and including a pair of substantially parallel side rails and ladder rungs extending between the last mentioned side rails at substantially equal intervals therealong and disposed on corresponding edges thereof, means pivotally connecting said second section at one end thereof to said first section near said one end of the latter, said second section having three operative positions relative to said first section in one of which the second section is received between the side rails of the first section with the edges of the side rails of the second section remote from the associated rungs bearing against the edges of the steps disposed intermediate the width of the first section side rails, in the second of which both of said sections diverge from said pivotal connection with the rungs of said second section at the side of the latter remote from said first section, and in the third of which said second section extends outwardly from said one end of said first section with the rung carrying edges of the side rails of said second section in substantial alignment with the first section side rail edges from which said steps extend, the rung carrying edges of the second section side rails bearing against the ladder rung of said first section, said pivotal connection including a lost motion arrangement to permit movement of said second section relative to said first section between said first and third positions, and a platform pivotally connected at one end to one of said sections adjacent said pivotal connection and engageable at its other end with the other of said sections to releasably secure said sections in said second position.
